ADVERTISING DISPLAY HOLDER

Juan P. Roselló, Sunnyside, Long Island, N. Y.

Application November 12, 1937, Serial No. 174,140

13 Claims. (Cl. 248—174)

This invention relates to a holder for menus, place-cards, etc., and for displaying articles such as bottles, boxes, and items of jewelry.

Generally, the invention seeks to provide a support or holder preferably made of paper, fibre, card-board, or the like, which is adapted to hold and support upon a table, a menu card or a place-card; or to display upon a counter or in a show window, articles of jewelry, or bottles, boxes, and similar articles.

The invention contemplates the provision of an article holder which is relatively inexpensive, capable of being formed from printed or lithographed material such as cardboard or fibre to provide a pleasing, attractive, and sales-inducing item, and which may be blanked in dies and provided with score or fold lines adapting it to be folded and erected into article-holding condition in a quick and easy manner.

More specifically, the invention seeks to provide a holder of this character which is formed of a single piece of printed or lithographed paper-like material folded to provide a stable support or pedestal and bearing ornamentation, indicia, or advertising matter, and one which may be transported, handled, and stored in knock-down flat condition, and which may be readily erected for use when desired.

The invention also seeks to provide a holder of this character in which may be incorporated a match pack which is readily accessible for use.

With the foregoing and many other objects, features, and advantages in mind, the invention may be realized in the several forms of its embodiments as illustrated in the accompanying drawings, upon which the following detailed specification is based.

In the drawings:

Fig. 1 is a perspective view of a holder of the character set forth particularly adapted for supporting menu cards or the like.

Fig. 2 is an end view thereof.

Fig. 3 is a view of the blank from which the holder shown in Figs. 1 and 2 is formed.

Fig. 4 is an end view of another form of holder.

Fig. 5 is a vertical sectional view of still another form.

Fig. 6 is a similar view of another modified form.

Fig. 7 is a plan view of a holder formed to support a bottle or similar article.

Fig. 8 is a front view thereof.

Fig. 9 is a vertical sectional view of a holder in which is incorporated a match pack.

Fig. 10 is a similar view of another form of the invention shown in Fig. 9.

Fig. 11 is a side view showing the manner of obtaining access to the matches.

Referring to the drawings in greater detail and more particularly to Figs. 1, 2, and 3, the support or holder is formed of a single piece of card-board, fibre, or the like, blanked in a die and provided with score or fold lines, as shown.

The holder is formed with two uprights 15 and 16 contiguous to the base portions 17 and 18, which in turn are joined with the base supporting portions respectively 19 and 20. Score lines are formed at 21 and 22 between the respective portions 15 and 17, and 16 and 18. Similarly, score lines 23 and 24 are formed between the respective portions 17 and 19, and 18 and 20. The portions 19 and 20 are joined by end connecting tabs 25 and a slit 26 is defined by said portions 19 and 20 and said connecting tabs. So that bending may be had between the portions 19 and 20 score lines 27 between said portions and the tabs 25 are formed. For the same reason, slits at 28 are provided.

The holder is assembled by introducing the upright portions 15 and 16 through the slit 26 and arranging the score lines in folds such as shown in Figs. 1 and 2. Stability is given the support thus formed by providing the shoulders 29 on the portions 15 and 16, said shoulders being engaged by the under surfaces of the tabs 25 to maintain the tabs in spaced apart relation with the base portions 17—18. In this manner the base support portions 19 and 20 are disposed at an incline so that they may engage the upright members 15 and 16 at a point spaced from the score lines 21 and 22 and thus effectively support said members.

The holder thus formed is adapted to support a menu card or place card C as shown in Fig. 1 and the exposed surfaces of the holder are peculiarly adapted to bear printed or lithographed ornamentation, indicia, or advertising matter.

As shown in Fig. 4, one of the upright members such as 16^a may be made somewhat shorter than the member 15 to afford greater facility in introducing a card between them. Also, the several score lines 27 may be replaced by a single score line 27^a between the base support portions 19 and 20 and thus eliminate the tabs 25.

The foregoing structures, while quite desirable, would necessarily have to be formed of double coated stock if all of the exposed surfaces are to

bear the mentioned ornamentation, etc., since the exposed surfaces of the upright members 15 and 16 are the opposite surface of the exposed surfaces of the base support portions 19 and 20. For this reason it is desirable to form one of the base portions such as 17 with a slotted opening 30 into which the upright member 16 may be introduced before that member and the other member 15 are passed through the slit 26. It is thus seen that the previously exposed surfaces of said members are now in back-to-back relation and, therefore, concealed, and that the previously concealed surfaces which form a continuation of the exposed surfaces of the portions 19 and 20, are now exposed. This holder may, therefore, be formed of single coated stock, bearing printed matter only on one face. The opening 30, when the holder is in use, is entirely concealed, and the outward appearance thereof is the same as that of the forms previously described.

In the form of the invention shown in Fig. 6, the upright members 15 and 16 may be made relatively short and in this instance may be used for supporting and displaying an article of jewelry, such as the finger ring R. Also as shown, the material forming the opening 30 may not be removed but may remain as a tongue 31 having engagement with an adjacent portion of the base member 18 to assist in maintaining the holder in assembled relation.

Another preferred form of the invention is shown in Figs. 7 and 8 wherein the upright members 15 and 16 are formed with cut-outs to provide the respectively spaced upright portions 32 and 33. The holder shown is designed to support an article such as the bottle B which is adapted to rest upon the edge 34 formed in the upright members and to be held in upright position by the outwardly flared portions 35 of the spaced upright portions 32 and 33. The base support portions 19 and 20 may each be cut away as at 36 to accommodate the bottle, and in other respects the holder may be similar to those previously described.

As shown in Fig. 9, the holder may have incorporated therein a match pack 37 held in position between the upright portions 15^b and 16^b. In the present instance, the portion 15^b is extended to provide a flap 38 adapted to cover the match pack and be tucked between said match pack and the free end of the member 16^b. The latter may be provided with a match-striking surface 39 and the menu or display card C may be supported by the holder by introduction between the upright 16^b and the flap 38. This structure may also follow in other details those previously described.

An alternate form of holder in which a match pack is incorporated, is illustrated in Figs. 10 and 11. In this form the previously mentioned flap 38 is extended to terminate at or adjacent the base and is not intended to be lifted for exposure of the matches. Access to the matches may be had by providing fold or score lines 40 and 41 transversely on the portions 15^b and 38 and also providing a slot or opening 42 in the portion 43 which connects said members, and pressing downward on the portion 43 so that the portions 15^b and 38 assume the folded condition shown in Fig. 11. The matches are now accessible for extraction of one of them and upon release of the pressure on the portion 43, the members 15^b and 38 will spring upward to again conceal the matches and in this condition the match-striking surface 39 may be safely used without possibility

of accidental ignition of the match pack by flying sparks or the flame of the ignited match. In other respects, this form of the invention follows those previously described.

While the invention has been illustrated in several preferred forms of its embodiment, it is apparent that the principles set forth may be incorporated in other forms not here disclosed, without departing from the spirit and scope of the invention as claimed. Hence, the prior art rather than the instant disclosure should form the basis of interpretation of the scope of the invention as defined in the following claims.

What I claim as new and desire to secure by Letters Patent, is:

1. An article holder comprising a sheet provided with score lines and a centrally disposed transverse slit, the end portions of said sheet being passed through said slit to form two coacting article holding portions, the central portions of the sheet forming support members for the article holding portions, and the remaining portions of the sheet forming the base portion of said article holder.

2. An article holder comprising a sheet provided with score lines and a centrally disposed transverse slit, the end portions of said sheet being passed through said slit to form two coacting article holding portions, the central portions of the sheet forming support members for the article holding portions, and the remaining portions of the sheet forming the base portion of said article holder, one of the latter portions being formed with an opening for the introduction therethrough of one of the article holding portions.

3. An article holder comprising a sheet formed with two central portions having a slot between them and connected at their opposed ends, an intermediate portion connected with each central portion, an end portion connected with each intermediate portion, and fold lines between all of the adjacent portions of said sheet whereby said sheet may be folded to pass the end portions through said slot to form coacting article holding members supported in upright relation by said central portions and disposed at right angles to the intermediate portions which form the supporting base therefor.

4. An article holder comprising a sheet provided with score lines and a centrally disposed transverse slit, the end portions of said sheet being passed through said slit to form two coacting article holding portions, the central portions of the sheet forming support members for the article holding portions, and the remaining portions of the sheet forming the base portion of said article holder, the end portions being formed with shoulders having engagement with said support members to maintain the base portion and the part of the support members adjacent the slit, in spaced apart relation.

5. An article holder comprising a sheet formed with two central portions having a slot between them and connected at their opposed ends, an intermediate portion connected with each central portion, an end portion connected with each intermediate portion, each of said end portions being formed with shoulders, and fold lines between all of the adjacent portions of said sheet whereby said sheet may be folded to pass the end portions through said slot to form coacting article holding members supported in upright relation by said central portions and disposed at right angles to the intermediate portions which

form the supporting base therefor, the mentioned shoulders having engagement with the said central support members at their points of connection to stabilize the holder in its folded condition.

5 6. In an article holder of the character described and formed of a single sheet, a base formed by two remote portions of said sheet, one of said portions being provided with an 10 opening, a member connected with each base portion and adapted to assume a position normal to its connecting base portion, the member connected with the base portion not having the opening being adapted to be passed through the 15 mentioned opening in the other base portion.

7. An article holder comprising a sheet of material bearing indicia on one face thereof, said holder being formed with a base portion, an article holding portion comprising two members in 20 contacting relation, and supporting portions for the latter, the exposed surfaces of the mentioned article holding members and the supporting portions bearing the mentioned indicia.

8. An article holder comprising a sheet provided with score lines adapting said sheet to be 25 folded to form a base portion, two coacting article holding portions, said latter portions each being provided with a cut-out for the reception of an article and formed with outwardly flared 30 article engaging edges, and support members for the article-holding portion.

9. An article holder comprising a sheet provided with score lines and a centrally disposed opening, the end portions of said sheet being 35 passed through said opening to form two coacting article holding portions, the central portions of the sheet forming support members for the article holding portions, and the remaining portions of the sheet forming the base portion 40 of said article holder, the mentioned end portions being each formed with end cut-outs for the reception of an article and provided with outwardly flared article engaging edges.

10. An article holder comprising a sheet provided with score lines adapting said sheet to be 45 folded to form a base portion, and two coacting article holding portions, support members for the article-holding portions, and a match

pack positioned between the latter two portions, one of said portions being extended to form a flap adapted to cover said match pack.

11. An article holder comprising a sheet provided with score lines adapting said sheet to be 5 folded to form a base portion, two coacting article holding portions, support members for the article-holding portions, a match pack positioned between the latter two portions, one of said portions being extended to form a flap 10 adapted to cover said match pack, and provided with a transverse opening intermediate its length and with transverse fold lines adapting said latter portion to be folded to expose said match pack through said opening for the extraction of 15 one of said matches.

12. An article holder comprising a sheet provided with score lines and a centrally disposed transverse slit, the end portions of said sheet being passed through said slit to form two coacting article holding portions, the central portions of the sheet forming support members for the article holding portions, and the remaining portions of the sheet forming the base portion of 20 said article holder, and a match pack positioned between the mentioned article holding portions, one of said latter portions being extended to form 25 a flap adapted to cover said match pack.

13. An article holder comprising a sheet provided with score lines and a centrally disposed transverse slit, the end portions of said sheet being passed through said slit to form two coacting article holding portions, the central portions of the sheet forming support members for 30 the article holding portions, the remaining portions of the sheet forming the base portion of said article holder, a match pack positioned between the mentioned article holding portions, one of said latter portions being extended to form 35 a flap adapted to cover said match pack, and provided with a transverse opening intermediate its length and with transverse fold lines adapting said latter portion to be folded to expose said match pack through said opening for the extraction of 40 one of said matches.

JUAN P. ROSELLÓ.
